UNITED STATES PATENT OFFICE

WILLIAM H. H. SPAULDING, OF PERU, INDIANA.

ADJUSTABLE GRATE FOR STOVES.

SPECIFICATION forming part of Letters Patent No. 376,758, dated January 24, 1888.

Application filed May 17, 1887. Serial No. 233,498. (No model.)

To all whom it may concern:

Be it known that I, WILLIAM H. H. SPAULDING, a citizen of the United States of America, residing at Peru, in the county of Miami and State of Indiana, have invented certain new and useful Improvements in Adjustable Grates for Stoves, of which the following is a specification, reference being had therein to the accompanying drawings.

- 10 My invention relates to adjustable grates for stoves; and it has for its object to provide a grate which, while being capable of use with small stoves, may be readily adjusted to fit stoves of larger size.
- 15 The invention consists in a certain novel construction and arrangement of parts, which will first be described in connection with the accompanying drawings, and then pointed out in the claims.
- 20 Figure 1 of the drawings is a top plan view of my improved grate with one extension-plate removed. Fig. 2 is a plan view of one of the extension-plates. Fig. 3 is an end elevation of the grate, looking in the direction of the arrow.

25 A represents the grate. It is cast in one piece of a length to suit stoves of small size, and has screw-holes formed in each end, as at *h*, for the attachment of extension-plates, hereinafter described, only one of said holes, however, being seen.

30 In order to lengthen the grate to suit stoves of larger size, I employ two extension-plates, B C, one at each end of the grate. These plates are formed alike, except that the vertical slots (hereinafter described) are in opposite ends of the respective plates. Each extension-plate is formed with a central web, *d*, in which there is a longitudinal slot, *l*, extending the whole length of the plate between its end bars. A vertical slot, *v*, is formed in the left-hand bar of plate B, and a like slot is formed in the right-hand bar of plate C. Each

of the extension-plates has a leg, *L*, cast on its outer bar, to serve as a support for the grate. 45 Plates B and C are adjustably secured to the grate by means of screw-bolts *b*, passing through the longitudinal slots in the plates and the holes *h* in the grate, and provided with nuts *n*. 50

H represents the fastening-hook (one for each plate) adjustably secured to the plate by a screw-bolt, *s*, passing through the hook and the vertical slot, and provided at its lower end with a nut, *t*, as seen in Fig. 3.

55 It will be readily seen on inspection of the drawings that the grate can be adjusted to fit stoves of different sizes by simply adjusting the extension-plates on the grate, and also that the hooks can be so adjusted as to engage 60 with the lugs on the stove in whatever position the lugs are likely to be located.

Having thus described my invention, what I claim as new, and desire to secure by Letters Patent, is—

65 1. The combination, with a grate constructed as described, of two extension-plates, one adjustably attached to each end of the grate, and two fastening-hooks, one adjustably attached to each extension-plate, the said plates being 70 each formed with a longitudinal slot and a vertical slot, substantially as described, and for the purposes stated.

2. The extension-plates B C, each having a central longitudinally-slotted web, as *d*, a vertical slot, as *v*, and a supporting-leg, as *L*, and the hooks H, when combined with each other and with the grate A in the manner above set forth.

75 In testimony whereof I affix my signature in presence of two witnesses.

WILLIAM H. H. SPAULDING.

Witnesses:

JAMES M. BROWN,
NOTT N. ANTRIM.
